UNITED STATES PATENT OFFICE

TERRENCE G. LOUIS, OF SPRINGFIELD, MASSACHUSETTS, ASSIGNOR TO WICO ELECTRIC COMPANY, OF WEST SPRINGFIELD, MASSACHUSETTS, A CORPORATION OF MASSACHUSETTS

BREAKER-POINT MECHANISM

Application filed September 12, 1927. Serial No. 219,116.

This invention relates to improvements in breaker point mechanism of the type wherein one of the breaker points is moved relatively to the other by a reciprocable plunger sliding in a suitable guide.

An example of a breaker point mechanism, of the type alluded to, will be found in U. S. Letters Patent No. 1,555,548, granted September 29, 1925 on a joint invention of Phelps 10 Brown, Harold H. Clark, Terrence G. Louis and Ira E. Hendrickson. Breaker point mechanism of the general type shown in this patent, lends itself nicely to the requirements of a magneto of the reciprocating armature 15 type and is commonly used therewith, as shown for example in my prior U. S. Letters Patent No. 1,517,997, granted December 2, 1924.

This particular type of breaker point mechanism includes a plunger for moving one of the breaker points and a guide in which the plunger slides. This plunger and guide have heretofore been made of metal and the relatively slidable bearing surfaces thereof require lubrication. While provisions are readily made for lubricating these parts, it is not so easy to control the lubrication within close limits to just the amount necessary. If lubrication is excessive or deficient, undesirable 25 conditions are created. For example, if the relatively slidable parts do not receive enough oil, cutting of the bearing surfaces results and the small metal particles worn off may eventually reach and lodge between the co- 30 operating breaker points. On the other hand, if these parts receive the least bit too much oil, the excess oil may reach and lodge between the breaker points. With either of these conditions there is an increase in the 35 disruptive effect of the arc between the contacting faces of the breaker points and an increased disturbance of the metal particles in such contacting faces. While by the use of the invention of said first named patent, 40 which is likewise embodied in the breaker point mechanism of the present invention, the points are redressed on each engagement by bringing them together with a percussive blow, the force of which is carefully gauged 45 so as to put back into place the disturbed par-

ticles of metal, whereby the breaker points will still function properly notwithstanding the adverse influences, referred to, it is nevertheless desirable to eliminate the trouble at the source. That is, while excessive or deficient lubrication results in damage to the points which can be repaired, it is better to prevent, or at least substantially reduce, the damage and thereby reduce the repair work which needs to be done by the redressing action of the percussive blow. The force of such blow must be adapted to the work in hand and will vary according to the amount of redressing necessary. The variation in force is secured by varying the speed and/or mass of the plunger. By reducing the amount of redressing to be done, one can use a lighter blow and is not restricted to such close limits as to the force of the blow. This means greater freedom as to the choice of the mass and speed of the plunger.

This invention is concerned, among other things, with the solution of the special lubrication problem above set forth and, to this end is directed to the provision of a breaker point plunger and a guide in which the same slides, wherein no lubrication is required for the bearing surfaces and wherein the undesirable conditions heretofore arising from excessive or deficient lubrication are avoided. The construction is also such as to protect the breaker points from oil which is used for lubricating other parts of the magneto. That is, the construction not only requires no lubrication but it also tends to exclude oil from any source from passing up the breaker point tube and reaching the breaker points.

To this end, at least one of the two co-operating bearing surfaces is made of felt or some material having similar characteristics. Usually, the plunger is constructed with a bearing surface of felt although it is possible to so construct the guide. It is sufficient that one of the two bearing surfaces be so constructed and the other may be of metal, bakelite or any other of many materials which will work with the felt. The particular material used for the bearing surface, with which the felt bearing surface is engaged for relative sliding movement, is or-

ordinarily not material although I prefer, for certain other reasons to use bakelite or the like. The felt bearing surface slides nicely over its opposing bearing surface without requiring any provision for lubrication. Moreover, the felt, in itself tends to exclude the oil which might in some cases enter the base of the breaker point tube from other parts of the magneto which have to be lubricated.

10 The invention also has for an additional object to provide a breaker point construction which is not only simple in form and adapted for manufacture at low cost but which is also durable, effective, efficient and substantially fool proof.

15 In many cases, the magneto includes a body of bakelite or similar material, which houses the coils of the magneto, and the breaker point mechanism is so located with respect to other parts of the magneto that it has to be housed in this body of bakelite. With the prior construction of the breaker point mechanism, a metal guide tube had to be set into the bakelite to receive the metallic breaker-point plunger and these relatively slideable parts had to fit within close tolerances. With the present construction, the breaker-point guide can consist simply of a hole in the bakelite body, whereby the expense of the 20 metal insert is saved. The felt plunger then slides on the bakelite wall of this hole and works nicely in cooperation therewith, forming a guide for the movable breaker point and requiring no lubrication. The former 25 necessity for working to close tolerances in finishing the breaker point plunger and its guiding tube no longer exists. The felt plunger will work in a hole which is undersize as well as one which is oversize within 30 relatively wide tolerances.

35 Other objects and advantages will appear in the following description and will be pointed out in the appended claims.

40 The invention will be disclosed with reference to the accompanying drawings, in which:—

45 Fig. 1 is a front elevational view partly in section, of a magneto showing a breaker point mechanism, embodying the invention applied thereto;

50 Fig. 2 is an end elevational view, partly in section, showing the breaker point mechanism and its relation with the magneto; and

55 Fig. 3 is a fragmentary sectional view, taken similarly to Fig. 1 and showing the constructional details of the breaker point plunger.

60 In these drawings I have shown the invention as applied to a magneto of a type in which it would ordinarily be easy for oil to enter the breaker point guide tube and reach the breaker points. However, the breaker point mechanism of this invention has worked satisfactorily in a magneto such as shown. 65 That is, it has effectively stopped the entrance

of oil to the breaker points in a magneto which, by reason of certain features of design, is especially liable to this trouble.

70 The magneto is of a known type and will require but brief description. It is of the type wherein an armature such as *a*, normally in contact with magnetic poles, such as *p*, represented by the lower end faces of a pair of cores *c*, is periodically moved away from said poles to generate an ignition spark in an electrical winding (not shown). The functional operation of the magneto and the general type of construction, including the mechanism for operating the armature, are substantially the same as disclosed in my 75 copending application Serial No. 133,493, filed September 3, 1926.

80 Particularly, the breaker point mechanism of this invention has the same function and is operated in the same manner as disclosed in said application. The breaker points are shown at 5 and 6, the former in this case being fixed and insulated and the latter movable and in electrical connection with the frame of the magneto. The movable point 6 is carried by the vertically reciprocable plunger shown which slides in a hole 7 formed in a body 8 of bakelite, or the like. The breaker point plunger has a stem 9, which passes loosely through an abutment 10 on armature *a*. Fixed to stem 9 and at a point below abutment 10 is a collar 11 which constitutes an abutment adapted to be engaged by the first named abutment during the downward flight of the armature. A spring 12, acting against collar 11, tends to hold the breaker points in contact. The armature *a*, when moved away from poles *p* sufficiently so that abutment 10 engages abutment 11, will move stem 9 downwardly against the stress of spring 12 and separate the breaker points. The latter are subsequently reengaged by spring 12 on the return stroke of armature *a* as the abutments 10 and 11 eventually become disengaged. The described arrangement is substantially 100 the same as disclosed in said application.

105 The breaker point plunger is, however, of novel construction. It includes one or more bodies of felt *f*, or like material, which slide in bearing engagement with the walls of hole 110 7. The latter forms the guide for the plunger. This guide, as shown, is formed of bakelite but this is not essential to the successful use of the felt plunger notwithstanding that it is desirable for the special reasons 115 above pointed out. The plunger and guide are usually, although not necessarily, cylindrical and the plunger may consist simply of one cylindrical body of felt, as shown in Fig. 3, or it may and desirably does, consist of a plurality (two as shown in Fig. 1) of longitudinally spaced cylindrical bodies of felt. The use of more than one body of felt makes it more difficult for oil to reach the breaker 120 points, especially if these bodies are axially 125 130

separated by a distance in excess of the stroke of the breaker point plunger, as shown. If oil creeps up past one of the felt bodies, it will lodge in the space between the bodies and will remain in contact with the lower body without getting an opportunity to reach the other body on account of the space being longer than the stroke of the plunger. That is, the lower end of the upper body never descends in hole 7 as low as the uppermost level to which oil can be raised by the upper face of the lower body.

As a convenient way of forming the bodies *f*, I construct them of a series of felt washers *w* mounted in a vertical stack on stem 9 and clamped together under axially applied pressure. Conveniently, stem 9 has a flange 14 near its lower end on which the base of the stack of washers *w* rest. Stem 9 terminates short of the stack of washers and is bored out and threaded, as at 15, to receive a threaded stem 16 which carries a nut 17 and, above this nut, the breaker point 6. A washer 18 encompassing stem 16 below nut 17 presses against the top of the stack of washers *w*. By turning nut 17 and thereby threading stem 16 into hole 15, the stacked washers *w* may be placed under sufficient pressure and clamped together. This pressure is a moderate one, such as can be obtained wholly with the means shown, as distinguished from heavy pressures which would compress the felt material to so high a degree that it would lose all its resiliency and become virtually like metal and would then require lubrication as much as metal. The compression is purposely moderate so that the felt material retains a certain amount of its resiliency. In the case where two bodies of felt are used, as in Figs. 1 and 2, the construction is the same except that a spacing collar 19 is applied between the two stacks of washers. These two stacks are clamped together under pressure by the single means above described.

While the felt bodies may be otherwise constructed, according to some features of the invention, the described construction will be found simple and well adapted to practical manufacture and is therefore desirable, important and preferred.

The most important characteristic of the felt is its ability to slide in bearing engagement with a guiding surface without receiving lubrication. Doubtless this characteristic is due to its inherent qualities of non abrasiveness, non-friability and elasticity or resiliency. Other materials, possessing these inherent qualities or the aforesaid characteristic, may be used and I intend, by the use of the term "felt", to cover substances of an equivalent nature. As a matter of preference, felt is used and I have found it important to use a high grade of felt, such as woven felt used on tennis balls. While ordinary pressed felt can be used, it tends to frazzle out

and liberate small whisker-like fibers, which may find their way to and lodge between the breaker points and thereby create an obviously undesirable condition.

The important consideration is to have one of the two cooperating bearing surfaces of felt or equivalent material. The nature of the other bearing surface is ordinarily immaterial. It follows that either the guide or the plunger may be of felt. As a practical matter it will usually be found more feasible to construct the plunger of felt rather than the guide but the latter is nevertheless possible and considered to lie within the scope of this invention.

While various materials may be used for the bearing surface, which cooperates with the felt, bakelite has been found to work in an ideal manner. In the particular magneto shown, the bakelite housing 8 exists and is so located and disposed that the interrupter mechanism must be, for the most part, housed therein. According to prior practice, a metal guide tube would have to be secured in the bakelite to receive the metallic breaker-point plunger. According to this invention, such a tube is unnecessary because a satisfactory guide is had simply by forming a hole in the bakelite itself. Since the felt plunger enables one to dispense with the metal guide tube and use a guide tube which is in itself an insulator, there is no longer any necessity for providing the insulation, formerly required, for the upper breaker point 5. There are then substantial advantages relating to economy in manufacture in the exact arrangement disclosed, wherefore such arrangement is important and preferred although not necessarily essential so far as the broader aspects of the invention are concerned.

In the magneto shown, the housing 8 rests upon a lower housing 20, which is somewhat similar to the crankcase of an automobile in that it contains the supply of lubricant. A thick felt pad 21 saturated with oil lies in the bottom of housing 20 and oil is conducted from the pad by wicks 22 to various bearings of the magneto. The point is that the lower housing contains oil and the lower end of the breaker point plunger is very close to the oil supply. The space limitations are so close that the armature almost touches the pad 21. The spring 12 also passes through the felt pad 21 and, as it works up and down, oil tends to creep up the same. These points are mentioned as factors which would ordinarily make it easy for oil to reach the breaker points. The conditions here are such that it would be exceedingly difficult with the former types of breaker point mechanisms to prevent oil from reaching the breaker points. The problem of excluding oil from the breaker points of the illustrated magneto is therefore a difficult one. Nevertheless, this prob-

lem has been adequately and satisfactorily solved by the construction disclosed.

The invention has been disclosed herein, in an embodiment at present preferred, for illustrative purposes but the scope of the invention is defined by the appended claims rather than by the foregoing description.

What I claim is:

- 10 1. In breaker point mechanism, a reciprocable plunger for moving one of the breaker points and a guide therefor, said plunger and guide having cooperating bearing surfaces one of which is composed of felt-like material.
- 15 2. In breaker point mechanism, a reciprocable plunger for moving one of the breaker points and a guide therefor constructed of bakelite or the like, that portion of the plunger which is slidably engaged with said guide being composed of felt-like material.
- 20 3. Breaker point mechanism, comprising, a reciprocable plunger, a breaker point carried thereby, a guide for the plunger composed of bakelite or the like, and a breaker point mounted in and insulated by said bakelite guide and so positioned as to be engaged by said first named breaker point, said plunger having a surface of felt-like material in bearing engagement with said guide.
- 25 4. In breaker point mechanism, a reciprocable plunger for moving one of the breaker points and a guide with which said plunger is slidably engaged, said plunger including a central stem, a series of superimposed felt washers mounted on said stem, and means for forcing them together axially under pressure, said felt washers forming a cylindrical body the periphery of which is in bearing engagement with said guide.
- 30 5. In breaker point mechanism, a reciprocable plunger for moving one of the breaker points and a guide with which the plunger is slidably engaged, said plunger having a plurality of axially spaced bodies of felt in bearing engagement with said guide.
- 35 6. In breaker point mechanism, a reciprocable plunger for moving one of the breaker points and a guide with which the plunger is slidably engaged, said plunger having a plurality of axially spaced bodies of felt in bearing engagement with said guide, said bodies being spaced one from the other by a distance greater than the stroke of said plunger.

In testimony whereof I have affixed my signature.

TERRENCE G. LOUIS.
